US0D1095289S

(12) **United States Design Patent** (10) **Patent No.:** **US D1,095,289 S**
(45) **Date of Patent:** **** Sep. 30, 2025**

(54) **WATCHBAND**

(71) Applicant: **SHENZHEN DO INTELLIGENT TECHNOLOGY CO., LTD.,**
Guangdong (CN)

(72) Inventors: **Yansheng Zhu**, Guangdong (CN);
Yanxiong Zhu, Guangdong (CN)

(73) Assignee: **SHENZHEN DO INTELLIGENT TECHNOLOGY CO., LTD.,**
Guangdong (CN)

(**) Term: **15 Years**

(21) Appl. No.: **29/868,561**

(22) Filed: **Dec. 7, 2022**

(30) **Foreign Application Priority Data**

Oct. 11, 2022 (CN) 202230670358.0

(51) **LOC (15) Cl.** **11-01**

(52) **U.S. Cl.**

USPC **D11/3**

(58) **Field of Classification Search**

USPC D11/1-5; D10/32

CPC A44C 5/0053

(57) **CLAIM**

The ornamental design for a watchband as shown and described.

DESCRIPTION

FIG. 1 is a front perspective view of a watchband showing our new design;

FIG. 2 is a back perspective view thereof;

FIG. 3 is a front view thereof;

FIG. 4 is a back view thereof;

FIG. 5 is a side view thereof;

FIG. 6 is the other side view thereof;

FIG. 7 is a front end view thereof;

FIG. 8 is a back end view thereof;

FIG. 9 is an enlarged detail view of the portion marked "9" of FIG. 1;

FIG. 10 is an enlarged detail view of the portion marked "10" of FIG. 2;

FIG. 11 is an enlarged detail view of the portion marked "11" of FIG. 2; and,

FIG. 12 is a front perspective view showing the combination state of the two parts in FIGS. 1-6.

The broken lines shown in the drawings represent portions of the watchband that form no part of the claimed design. The dot-dash broken lines enclosing portions of the watchband in FIGS. 1 and 2 and illustrated in enlarged views in FIGS. 9, 10 and 11 form no part of the claimed design.

1 Claim, 12 Drawing Sheets
